JAMES NICOLSON BAILEY, OF STRETFORD, ENGLAND, ASSIGNOR TO THE WESTINGHOUSE MACHINE COMPANY, A CORPORATION OF PENNSYLVANIA.

PROPULSION OF VESSELS IN WATER.

993,638.

Specification of Letters Patent. Patented May 30, 1911.

Application filed May 17, 1909. Serial No. 496,622.

To all whom it may concern:

Be it known that I, JAMES NICOLSON BAILEY, a subject of the King of Great Britain, and a resident of Stretford, England, have made a new and useful Invention in Improvements in or Relating to the Propulsion of Vessels in Water, of which the following is a specification.

This invention relates to the propulsion of vessels in water, such as ships, submarines, torpedoes and the like, and particularly to those cases in which an elastic fluid turbine is employed as the prime mover.

The use of an elastic fluid turbine which is directly connected to the propeller for the propulsion of vessels in water is attended by serious disadvantages due to the fact that in order to secure efficiency and economy an elastic fluid turbine should be run at a high speed, whereas the propeller should be run at a comparatively low speed. It is customary to make a compromise between the two, the turbine being run at a speed lower than is desirable and the propeller at a higher speed than is desirable, with the result that the turbine is more expensive and less efficient than would be the case if it could be run at a higher speed, and the best results are not obtained from the propeller. A further objection to the use of turbines directly connected to the propeller is that turbines as at present constructed cannot be reversed with the desired efficiency and it is therefore necessary to provide additional turbines for rotating the propeller in the opposite direction when it is desired to go astern.

It has already been proposed in order to overcome the above difficulties to use electric transmission between the turbine and the propeller and in one arrangement of this kind an elastic fluid turbine drives an alternating current generator which is electrically connected to an induction motor which drives the propeller. In this arrangement in order to enable the speed of the propeller to be varied, the induction motor used is of the slip ring type with adjustable resistances in the secondary circuit of the motor. This method of control is, however, open to serious objection, on account of the large size and heavy weight of the resistances, the difficulty of keeping them cool and the cost and difficulty of building a satisfactory controller.

The present invention has for its object to provide an improved system of electrical transmission between the turbine and the propeller which will allow of a high speed, and therefore economical turbine being employed, which is not subject to the objections above mentioned. As is well known the speed of an induction motor of the short-circuited rotor type is dependent, among other things, upon the frequency of the current supplied to its primary winding. By suitably constructing the alternating current generator so as to give currents of predetermined frequency, and also by so designing the motor that it will rotate at a given speed with currents of such predetermined frequency, any desired ratio of speed between the turbine and the propeller can be obtained which will remain constant. Under these circumstances the speed of the motor will vary in accordance with the speed of the generator, as variations in speed of the latter will alter the frequency of the current supplied to the motor.

In the present invention variation in the speed of the propeller is obtained by varying the speed of the turbine which will vary the frequency of the generator 2 and therefore the speed of motor 4, and for this purpose I preferably provide the turbine with means whereby the amount of steam or fluid passing to the turbine or turbines, is varied to meet the speed required.

According to my invention I provide an alternating current generator driven by the turbine and an induction motor for driving the propeller and I electrically connect the generator and the motor and interpose a reversing switch in the said connection.

In order that the invention may be clearly understood I will proceed to describe the same with reference to the accompanying drawings, in which—

Figure 1 is a diagrammatic view of a system of power transmission arranged in accordance with my invention, Figs. 2 and 3 being detail views of portions of the apparatus illustrated in Fig. 1.

Referring now to Fig. 1, the turbine which may be of any well known type is shown at 1, the rotor of which is carried upon or connected to the shaft which carries the rotor of a three-phase alternating current generator 2 which is electrically connected by means of conductors 3 to an induction motor 105

100

105

110

4; the rotor of which is directly connected to the propeller shaft 5. Located in the circuit leading from the generator 2 to the induction motor 4 is a reversing switch of any suitable type, here shown as comprising a contact arm 6 pivotally mounted at 7 and adapted to complete the circuit between contact pieces 8 connected to the supply circuit of the generator 2 and one or other of the sets of contact pieces 10, 11 electrically connected to the terminals of the motor in accordance with the desired direction of rotation of the motor, this reversal in the direction of rotation of the motor in accordance with the position of the contact arm 6 being due to the cross-connections 12 between the contact pieces 10, 11. The lower extremity of the arm 6 of the reversing switch is shown directly connected to the main controller handle 13 by means of a link 14. The main controller which is adapted to effect automatic operation of the steam admission valves of the turbine, in addition to controlling the position of the reversing switch, has its handle 13 pivotally mounted at 15 and the face plate 16 of the controller is rotatably mounted on the same pivot and is capable of being rotated independently of the rotation of the handle 13 by means of a wheel and worm mechanism 17 the wheel portion being formed upon the edge of the face plate and the worm being carried upon the shaft of a small induction motor 18, the terminals of which are connected by means of conductors 9 to a three-phase circuit of constant potential 88. A similar motor 20 is provided also connected to the same source of supply, the shaft of the motor carrying a worm wheel 21 acting upon a toothed wheel 22, the rotation of which by means of a rod 23 eccentrically mounted thereon effects the opening and closing of a valve 24 controlling the admission of steam to the turbine. The lower extremity of the rod 23 is pivotally connected to the stem of the valve 24 so as to permit the rod 23 to be moved out of alignment with the stem of the valve 24 when the wheel 22 is rotated. The motors 20 and 18 are adapted to be driven synchronously so that the position of the face plate of the controller shall correspond with the position of the valve controlling the admission of steam to the turbine.

I have illustrated the steam turbine valves and main controller as being some distance apart, which has necessitated a separate motor for the turbine valve and for the face plate of the controller, but under some circumstances it might be convenient to place the turbine valve governing mechanism and the main controller together in which case one motor would suffice to operate both the face plate of the controller and the valve of the turbine.

65 There are various ways of insuring syn-

chronous operation of the motors 18 and 20 but the means which I have illustrated comprise a regulating device dependent for its operation upon the difference in speed between the two motors and adapted to vary the amount of resistance included in the rotor circuit of the motor 18. This regulating device comprises differential wheel and worm mechanism operating a rheostat 25, the arm 26 of which is adapted to make contact with studs 27 connected through successively decreasing amounts of resistance to the slip rings 89 forming the terminals of the rotor windings of the motor 18. The arm 26 is connected to one end of a rod 28, the other end of which is pivotally mounted upon a worm wheel or floating wheel 29 in gear with worms 79, 80. The rotation of this wheel does not effect the movement of the arm 26 until the worms are rotated at different speeds, since the upper extremity of the rod 28 is pivoted to the center of the wheel 29; when, however, the worms 79, 80 are driven at different rates of speed, the wheel 29 will be raised or lowered, thereby varying the amount of resistance included in the circuit in accordance with the direction of movement of the wheel. This differential wheel and worm mechanism is operated by solenoids 30, 31, in opposition to springs 32, 33 respectively acting upon ratchet wheels 34, 35 attached to said worms and driven by pawls 36, as will be understood from inspection of the drawing (Fig. 2). In order to obtain intermittent action of the solenoids 30, 31 make and break contacts 85 are provided on both the motor shafts adapted to complete the circuit through a battery or from direct current bus bars 39 by means of conductors 91 at each revolution of the shafts of the motors 20, 18.

The steam chest of the turbine is indicated at 40 connected to the steam supply by means of pipe 41 and to the turbine by pipe 42. A pipe 43 connected to the steam chest admits steam to a separate compartment in the turbine casing comprising a number of blades or nozzles so arranged that on steam being admitted to this compartment an efficient braking of the rotor can be obtained. An arrangement of blades for this purpose will be understood by those familiar with the art and I have not considered it necessary to describe the same. The supply of steam to the turbine proper is controlled by the valve 24 before referred to, operated by the wheel and worm mechanism 21, 22 and an additional valve 44 operates to control the flow of steam to the turbine independently of the valve 24. This additional valve 44 operates in conjunction with a valve 45 controlling the supply of steam from the steam chest to the braking portion of the turbine and is so arranged that the opening of either of the said valves automatically

insures the closing of the other valve and vice versa. In order to effect this operation of these valves I have shown their stems connected respectively to opposite ends of a link 46 pivotally mounted at 47 and adapted to be rotated on its pivot, and thus to cut off the supply of steam to the turbine proper and open the valve leading to the braking section of the turbine, by means of a solenoid 48, acting in opposition to a spring 49 which normally holds the valve 45 controlling the supply of steam to the braking section of the turbine in a closed position. The main controller is provided with three primary positions "stop", "full ahead" and "full astern" indicated respectively by dotted lines a, a, a, b , and a, c , and the intermediate positions of the controller handle insure a corresponding increase or decrease in the supply of fluid to the turbine. The face plate of the controller is provided with two sets of contact pieces 50, 51 and 52, 53 and the controller handle is electrically connected by means of conductor 54 to one pole 25 of a battery or bus bar of direct current supply 39. The contact pieces 50, 51 are connected respectively to one terminal of solenoids 56, 57 by means of conductors 74, 75, the other terminals of the solenoids 56, 57 being connected to the battery by means 30 of a conductor 58. The contact pieces 52, 53 are connected respectively to contact pieces 60, 59 of a switch device 86 by means of conductors 76, 82 the contact piece 62 of switch device 86 being connected by means 35 of a conductor 63 to one terminal of the solenoid 48, the other terminal of the solenoid 48 is connected to the battery or direct current bus bars 39 by means of a conductor 40 87. The cores of the solenoids 56, 57 are operatively connected to the contact arm 81 of a switch device 64 adapted to control the operation of the motors 20, 18 said switch device comprising contact pieces 65 connected to the source 88 of three-phase supply 45 and contact pieces 66, 67 connected to the conductors 68 leading to the motors 20, 18. The arm 81 is normally held out of engagement with the contact pieces 66, 67 by means 50 of springs 90, 69. The main controller handle 13 in addition to effecting the operation of the reversing switch, effects the operation of the switch device 86 before referred to and is directly connected thereto 55 by means of link 14, the end of which is connected to a contact arm 77 pivotally mounted at 78 adapted to complete a circuit between the contact piece 62 and one or other of the contact pieces 59, 60 in accordance with the position of the reversing switch and the main controller handle.

In order that the reversing switch shall not be moved from a power position to a reverse position when the generator is rotating at a high rate of speed and generating

a high voltage, I provide a stop 70 attached to the core of a solenoid 71 adapted to be moved into an operative position against the action of a spring 72 to prevent such reverse movement of the contact arm 6 until a predetermined fall of voltage has occurred. The terminals of the solenoid 71 are connected to the circuit of the generator 2 by means of conductors 73, (Fig. 3).

The various circuits established in the different positions of the controller handle will be hereinafter explained in the description of the operation of the apparatus.

The operation of the apparatus is as follows: If the main controller handle is moved to the "full ahead" position indicated by dotted lines a, b , contact will be made between the controller handle 13 and contact piece 50. This will close the circuit leading from the battery or direct current bus bars 39 to the solenoid 56, by means of conductors 54 and 74, which will accordingly be energized. The arm 81 will therefore be moved into engagement with contact pieces 66, which will close the circuit leading from the three-phase alternating current supply 88 to the motors 20, 18. The motors 20, 18 therefore will be brought into operation, the motor 20 by means of the wheel and worm mechanism rotating the wheel 22 opening the valve 24 admitting steam to the turbine, and the motor 18 rotating the controller face plate 16 in a counter-clockwise direction by means of the wheel and worm mechanism 17. It should be noted that in passing from "stop" position to "full ahead" position or to an intermediate power position the solenoid 48 controlling the operation of the valve 45 governing the admission of steam to the braking section of the turbine is not energized owing to the circuit leading from the battery or direct current bus bars 39 through the controller to one terminal of this solenoid having been broken by the switch 86 and it is the purpose of this switch to break the circuit leading to the solenoid 48 which would otherwise be completed by reason of the controller handle 13 having been brought into engagement with the contact piece 52 or the contact piece 53 in all cases in which the controller is moved directly from a "stop" position to a power position either "ahead" or "astern" or from a power position directly to a "stop" position or to a higher power position when it is unnecessary to check the speed of the turbine. The motors 20 and 18 will continue to operate until the face plate 16 of the controller has been moved to a sufficient extent to break contact between the controller handle and the contact piece 50. Since as before explained, the speed of the motors 20, 18 must at all times correspond, the valve 24, when the motors have been brought to a stop owing to the solenoid 56 having become deenergized, will

be opened to correspond to the position of the controller handle. If, after the turbine has attained full speed it is desired to reduce the speed of the ship the controller handle is moved to a position between the "full ahead" and "stop" position the lever 13 will be brought into engagement with contact pieces 51, 53 on the controller face plate 16 by reason of the movement of the controller face plate when the controller was moved from "stop" to "full ahead" position. The circuit will be completed therefore from one pole of battery or direct current bus bars 39, conductor 54, controller hand 13, contact piece 51, conductor 75 to one terminal of the solenoid 57; the other terminal of the solenoid being normally connected to the other pole of the battery or direct current bus bars 39 the solenoid will be energized. The arm 81, therefore, will be brought into engagement with the contact pieces 67 which will complete the circuit leading from the alternating current supply 88 to the motors 20, 18 which will again be brought into operation, but in the reverse direction. At the same time as the circuit is completed through solenoid 57, circuit will be completed from one pole of the battery or direct current bus bars 39 to the controller handle 13 by means of conductor 54, contact piece 53, conductor 82, contact piece 59 of the switch device 86, contact arm 77, contact piece 62, conductor 63, to one side of the solenoid 48, the other terminal of solenoid 48 being normally connected to the other pole of the battery or direct current bus bars 39 by means of conductor 87 the solenoid 48 will be energized. This will rotate the link 46 upon its pivot which will close the valve 44 governing the admission of steam to the turbine and open the valve 45 admitting steam to the braking section of the turbine. Steam will be admitted therefore to the braking section of the turbine and the motors 20, 18 will continue to operate until the motor 18 has rotated the face plate 16 of the controller to an extent sufficient to break contact between the controller handle and the contact pieces 51, 53 when the motors 20, 18 will be brought to a stop and the supply of steam to the turbine will be reduced. The motors 20, 18 will be brought to a stop by reason of the solenoid 57 having become deenergized and the arm 81 returning to a neutral position under the action of spring 90. Contact being broken between the controller handle 13 and contact piece 53, the solenoid 48 will be deenergized and the link 46 will be rotated on its pivot under the action of the spring 49, consequently the supply of steam to the braking section of the turbine will be cut off and steam will be again admitted to the turbine. It will be seen that the response on the part of the turbine to the movement of the controller handle is very

quick owing to this braking of the rotor, and the supply of steam to the turbine is temporarily checked in all cases in which the controller handle is moved from a power position to a lower power position, owing to the movement of the valve 44, independently of the position of the valve 24.

If after the speed of the ship has been reduced it is desired to cut off the supply of steam to the turbine entirely without reversing the propeller, the controller handle 13 is moved to the "stop" position indicated by dotted lines a , a . The controller face plate 16 having been moved when the controller handle was moved from the "full ahead" to the intermediate position above described, this movement of the controller handle to "stop" position will bring the handle 13 again into engagement with the contact pieces 51, 53. This will complete the circuit leading from battery or direct current bus bars 39, conductor 54, controller handle 13, contact piece 51, conductor 75, to one terminal of solenoid 57. The solenoid 57 will be energized and the arm 81 will be again brought into engagement with contact pieces 67. This will complete the circuit between the three-phase supply 88, and the motors 20, 18 through the switch 64 and the motors 18, 20 will again be brought into operation. The motors 20, 18 therefore will continue to operate until the controller face plate has been moved to an extent sufficient to break contact between the controller handle and contact piece 51. When the circuit is broken, the motors 20, 18 will be stopped and the supply of steam to the turbine will be cut off. In this instance as before explained steam will not be admitted to the braking section of the turbine owing to the circuit leading to the solenoid 48 having been broken by the switch device 86 being moved into a neutral position in which the contact arm 77 is not in engagement with either of the contact pieces 59, 60. In cases in which it may be necessary to pass from an "ahead" position to an "astern" position of the controller, which may be possible when the controller handle is moved from a very low power position to a reverse position (in which case the solenoid 70 would not be in an operative position and prevent the movement of the reversing switch) the same circuits will be completed as in the case in which the controller handle was moved from a "full ahead" position to a lower power position, except that solenoid 48 will not be energized after the lever 13 has come to stop position a — a , and, the supply of steam to the turbine will be cut off until the handle 13 is moved to stop position, when solenoid 48 will be deenergized by contact arm 77 moving off of contact 59 which is electrically connected to contact 53, when steam will be again admitted to the

turbine which will quickly gather speed. During this movement of the controller handle the motor 20 will close the valve 24 owing to the rotation of the wheel 22, but since the circuit leading to the solenoid 57 will not be broken until the contact plate 16 has completed its movement the wheel 22 will continue to rotate and move the crank 23 past dead center, thereby eventually 10 opening the valve 24 to its correct extent.

If the controller handle 13 is moved from the lowest power position either ahead or astern or from an intermediate power position to a full power position, the circuit leading to the solenoid 48 will not be completed owing to the position of the switch device 86, for when the handle 13 is moved toward the *a-b* position, the arm 77 is in contact with 15 59 and lever 13 is in contact with 52 and not in contact with 53 and no circuit will be completed through magnet 48, from this it will be seen that steam will only be supplied to the braking section of the turbine when the controller handle is moved from a high- 20 power position to a lower power position, or from a power position to a reverse position, which will insure a quick response on the part of the turbine to the movement of the controller handle and the interval of 25 time during which steam is supplied to the braking section will depend upon the extent of movement of the controller handle, and therefore the amount of braking will depend upon the decrease in speed which it 30 is desired to effect. Several such controllers may be distributed about the ship in convenient positions, so that the ship may be controlled from any one position whichever may be selected.

Having now particularly described and ascertained the nature of my said invention and in what manner the same is to be performed, I declare that what I claim is:

1. In a mechanism of the class described, 45 a steam motor having a braking section, a generator driven by the motor, a reversible electric motor receiving energy from the generator, a controller adapted to reverse said electric motor, a valve device adapted 50 to cut off the supply of motive fluid from all sections of said steam motor except said braking section, and means for timing said valve device in accordance with the extent of movement of said controller.

55 2. In a power transmission system, a turbine, an electric generator driven by the turbine, a motor receiving energy from said generator, a controller for governing the supply of steam to the turbine and means

for effecting a reversal of the connections 60 leading from the generator to the motor and to automatically cut off the supply of steam to the turbine.

3. In a system of power transmission, a 65 turbine having a braking section, an alternating current generator driven thereby, a motor receiving current from said generator, a reversing switch between the motor and generator, and means controlled by said switch for cutting off the supply of steam 70 to the turbine.

4. In a system of power transmission, the combination of a turbine, an alternating current generator driven thereby, a motor receiving energy from the generator, a reversing switch in the circuit leading from the generator to the motor, a second source of generation, a motor-controlled valve for admitting steam to the turbine and receiving 80 its energy from the second source of generation, a rotatable contact plate for the main controller, a motor for imparting motion to said plate and receiving its energy from the second source of generation, a synchronizing device for the two last named 85 motors and means for closing the circuits for said motors when the reversing switch is operated.

5. In a system of power transmission, the combination of a turbine, an electrical current generator driven thereby, a motor receiving energy from said generator, a fluid pressure brake on said turbine, a steam casting having an inlet port and outlet ports 90 leading respectively to the generator proper and to the brake, a reversing switch between the motor and generator, and means controlled by the switch for closing one of the outlet ports and opening the other.

6. In a system of power transmission, a 100 turbine, a generator driven thereby, a motor receiving energy from said generator, a reversing switch in the circuit between the generator and motor, an auxiliary motor, a valve controlled by the auxiliary motor for 105 determining the amount of steam passing into the turbine, and means controlled by the reversing switch for controlling the auxiliary motor to determine the open position of said valve.

In testimony whereof, I have hereunto 110 subscribed my name this 30th day of April 1909.

JAMES NICOLSON BAILEY.
